(57) **CLAIM**

The ornamental design for a foot portion of a table leg, as shown and described.

DESCRIPTION

FIG. 1 is a perspective view of a foot portion of a table leg; FIG. 2 is an enlarged perspective view from the left side of the foot portion of a table leg shown in FIG. 1; FIG. 3 is an enlarged perspective view from the right side of the foot portion of the table leg shown in FIG. 1; FIG. 4 is a top view of the foot portion of a table leg shown in FIG. 2; FIG. 5 is a right side view of the foot portion of a table leg shown in FIG. 2; FIG. 6 is a left side view of the foot portion of a table leg shown in FIG. 2; FIG. 7 is a bottom view of the foot portion of a table leg shown in FIG. 2; and, FIG. 8 is a front view of the foot portion of a table leg shown in FIG. 2, with the rear view being the same. The broken lines are for environmental purposes only and form no part of the claimed design.
